MOLDED DECOY

Arthur H. Risch and Arthur J. Nelson, Wauwatosa, Wis., assignors to Pulp Reproduction Company, Milwaukee, Wis., a corporation of Wisconsin

Application December 14, 1950, Serial No. 200,708

3 Claims. (Cl. 43—3)

1

The present invention relates generally to improvements in the production of molded pulp articles or the like, and relates more particularly to improvements in the construction and assemblage of molded aquatic decoys.

A primary object of our present invention is to provide an improved decoy of the type used by hunters which is exceedingly light in weight but nevertheless exceptionally durable and susceptible of long usage and rough handling, which is simple and inexpensive in construction and capable of partial dismantling for storage or the like, and which furthermore possesses excellent balance and buoyancy on water.

It has, of course, been common practice for many years to use imitation decoys in hunting to lure game to desired localities. Although wood was customarily employed in the production of such decoys until relatively recent years, decoys of molded paper pulp have now become extremely popular and extensively used because of the light weight and low cost thereof plus the ability to mold the same into life-like shapes. However, despite the success enjoyed by these molded pulp decoys, several difficulties have heretofore been present in the manufacture of such articles. One of the major difficulties encountered is in the sealing of the opening necessarily left in the wall of the decoy body by reason of the suction molding process employed, particularly since such opening is usually left in the base or bottom wall so as not to detract from the life-like qualities or appearance of the decoy. Another serious problem heretofore encountered is in providing suitable balancing means for the hollow decoys while maintaining the proper buoyancy thereof to impart a true life-like appearance thereto while floating on water. Finally, considerable difficulty has also been encountered in attempting to minimize the storage space required for quantities of the decoys, especially during off-season storage without unduly affecting the ultimate cost and without undesirably weakening the final structure.

It is therefore a more specific object of our present invention to provide a new and improved molded pulp decoy which obviates all of the disadvantages and difficulties heretofore attendant prior devices of this general type.

Another specific object of the invention is to provide an improved decoy formed of molded paper pulp or the like and having a hollow body provided with an access opening in the front portion of the upper wall adapted to be closed by the neck portion of a separable molded head.

2

Another specific object of this invention is to provide an improved molded pulp decoy having a separable head member adapted to be readily secured to the body in a simple and effective manner so as to close the access opening to the body and permit adjustment of the head to various positions.

Another specific object of our invention is to provide an improved hollow molded decoy in which the anchor attachment means is protectively recessed in the base, and which furthermore requires no righting board or base closure plate to provide buoyancy and/or sealing.

Still another specific object of our present invention is to provide an improved hollow molded pulp decoy in which the base is formed with ribs and/or grooves adapted to aid in maintaining the decoy in proper position on water, and wherein the bottom may be readily and effectively sealed and weighted internally during manufacture.

A further specific object of the present invention is to provide an improved decoy which may be readily produced in large quantities of inexpensive and light weight materials by molding, and which may be quickly assembled in relatively few simple operations by a novice to provide a compact and durable final assemblage capable of being packed and/or stored in a minimum amount of space.

An additional specific object of the present invention is to provide an improved decoy comprising, a hollow molded body having a local recess near the front portion of the base and an access opening in the top wall above said base recess, anchor attachment means carried by the base within said recess, a layer of adhesive sealing material substantially covering the internal surface of the base, a head having a neck portion penetrating and closing said access opening, and means for maintaining said head in position with the neck portion thereof within said opening.

These and other specific objects and advantages of the present invention will be apparent from the following detailed description.

A clear conception of the several features constituting our present invention, and of the mode of constructing and of assembling aquatic molded pulp decoys embodying the improvements, may be had by referring to the drawing accompanying and forming a part of this specification, wherein like reference characters designate the same or similar parts in the various views.

Fig. 1 is a central longitudinal vertical section

through a typical duck type aquatic decoy formed of molded pulp and embodying our present improvements;

Fig. 2 is a transverse vertical section through the decoy, taken along the line 2-2 of Fig. 1; and

Fig. 3 is a transverse vertical section through the same decoy, taken along the line 3-3 of Fig. 1.

While the invention has been shown and described herein as being especially advantageously applicable to a typical aquatic duck decoy formed of molded paper pulp, it is not desired or intended to unnecessarily restrict or limit the scope or utility of the improvements by virtue of such limited embodiment, since the invention may obviously be more generally applicable to diverse types of decoys formed of any suitable moldable material.

Referring to the drawing, the typical aquatic duck decoy shown therein as embodying the invention comprises, in general, a hollow molded body 5 of fibrous material such as paper pulp formed with a local recess 6 in the base near the front portion thereof, anchor attachment means consisting of an eye 7 having a threaded shank 8 penetrating the base within the recess 6, an opening 9 formed in the top wall of the body 5 in substantial vertical alinement with the recess 6 for affording access to the inner end of the shank 8 of the attachment means, a head 10 adapted to normally seal the top opening 9, and means such as a resilient member 11 connected with the head 10 and with the shank 8 of the attachment means.

While the member 11 does, in fact, tend to secure or fasten both the head 10 and the attachment means 7, 8 in seating position, it is preferable to provide separate fastening means such as a lock nut 12 for the threaded shank 8; and it is also desirable to provide a washer 13 or the like externally of the recess wall for seating of the eye 7. To effectively seal the joint around the shank 8 of the anchor attachment means against leakage, a quantity of suitable adhesive sealing material such as asphalt or tar is poured directly over the inner end of the shank 8 to provide a layer 14 of sealing material over the fastener 12 and in direct contact with the shank 8; and a sufficient quantity of the sealing material should preferably be injected so as to extend the layer 14 over substantially the entire internal surface of the base, as shown, to thereby provide sufficient balancing weight to insure righting of the decoy on water as well as to reinforce the base. As an additional reinforcement for the base and to aid in properly balancing the decoy while afloat, the base is also formed with a central internally recessed keel 15 extending longitudinally of the decoy and terminating at the local recess 6 to conceal and protect the anchor attachment eye 7, and the keel recess is, of course, also lined with the thick adhesive sealing layer 14. If it is desired to further reinforce the base of the decoy body 5, reinforcement beams or corrugations 16 may be formed on opposite sides of the keel 15, and any desired number of such beams, also extending longitudinally of the base, may be provided. The head 10 of the decoy may also be formed of molded pulp or the like, and is preferably provided with a depending tubular neck portion 17 of reduced diameter adapted for insertion into the top opening 9 so that the adjacent annular flange 18 formed thereby may be seated directly against the upper wall of the body 5, the

head being pivotally movable to some extent to different positions of adjustment. To provide a means for connecting the member 11 with the head, a plug 19 of suitable material may be screwed within the end of the tubular portion 17, the plug 19 being provided with a bail 20 adapted to receive one end of the member 11, and the member 11 may conveniently assume the form of a tension spring, as shown, hooked at its lower end into an eye 21 or the like formed on the inner end of the shank 8 within the body 5.

In addition to the foregoing, the top opening 9 in the body 5 is preferably tapered, as shown, with the depending tubular reduced neck portion 17 of the head 10 being correspondingly externally tapered to insure positive seating and tight sealing between the head and body about the neck portion when the head is applied as described. Furthermore, to aid in positively correctly seating the head 10 while limiting pivotal movement thereof to the most natural life-like and common positions relative to the body 5, the front external breast portion of the body 5 is provided with a smoothly curved substantially frustroconical surface generated about the pivotal axis of the head and extending substantially from one side of the body to the other side thereof with the contour of the body 5 therebeyond gradually varying and finally terminating in a substantially flat top surface approximately parallel to the body base extending rearwardly of the top neck opening as shown, and the front nose or beak portion of the head 10 is formed with the lower external surface of a contour substantially corresponding to the smoothly curved adjacent exterior surface of the breast portion of the body 5 also as shown. By such construction, the beak portion of the head 10 and the breast portion of the body 5 will remain in substantially contacting relation when the head is turned relative to the body with the pivotal movement of the head being limited in an obvious manner to an arc of a length equal to the breast portion of the body having similar contour, thereby also resulting in a more durable construction in which the relatively fragile beak portion is somewhat reinforced by the breast portion of the body.

In the production of aquatic hunters' decoys embodying our invention, the hollow bodies 5 may be initially produced in a well-known manner with standard suction molding machines, the pulp being fed to the molds through the top opening 9; and the heads 10 may be produced in like manner, with the pulp being fed through the openings in the tubular neck portion 17. After the bodies and heads have been initially produced, they may be impregnated with a suitable water-proofing material, and the interiors of the shells 5 and 10 may be coated or impregnated with an adhesive sealing material such as asphalt, tar, or pitch. The attachment means 7, 8 may then be applied within the base recess 6 in an obvious manner and secured in place by the fastening means 12, after which a considerable quantity of the asphalt or tar may be poured through the top opening 9 directly over the recess 6 and attachment means 7, 8, the material being permitted to flow over substantially all of the internal surface of the base to provide the layer 14. The tension spring 11 may then be hooked into the eye 21 of the attachment means, and the other end of the spring may be hooked over the bail or the like formed on the plug 19 which may be applied to head 10 in an obvious manner, and the head may then be positioned

over the opening 9 with the tubular neck portion penetrating such opening. The head 10 may either be firmly secured in position by means of a suitable adhesive, or the adhesive may be omitted to permit pivotal movement of the head and subsequent removal thereof.

From the foregoing detailed description, it will be apparent that the present invention provides an improved decoy assemblage which is extremely simple and durable in construction, which may be produced in large quantities and at relatively low cost with inexpensive materials, and which may be molded to exceedingly life-like formation for effective usage. By reason of the improved construction, the usual bottom sealing and righting board is eliminated and the problem of sealing the usual bottom opening against water leakage is most effectively obviated. The keel 15 cooperates with the beams 16 and the inner layer of adhesive material 14 to reinforce and strengthen the base; and the keel 15 furthermore cooperates with the base recess 6 to protectively conceal the attachment means 7, 8 the eye of which may be used for tying an anchor line or the like thereto. The head 10 of the decoy may be rendered separable as indicated hereinabove so that the decoys may be readily stored or packaged for transportation in tiers one upon the other; and to aid in stacking thereof in a minimum amount of space, the top wall of each decoy body 5 may be formed with a central longitudinal groove or recess 22 adapted to receive the keel 15 of a body stacked thereon, the groove 22 extending rearwardly, for substantially the length of the body, from a point at the edge of an annular surface which surrounds the opening 9 and lies in a single plane to form a seat for the head 10. The head 10 may be readily applied, as indicated, by a novice, and both the body 5 and head 10 may be impregnated or coated in the usual manner for water-proofing and may be subsequently painted as desired. In the impregnation and application of the layer 14, suitable molten adhesive adapted to harden upon cooling may be utilized, and the layer 14 also aids in properly weighting the decoy body so as to maintain it in an upright position while floating.

It should be understood that it is not desired or intended to limit this invention to the exact details of construction or to the precise mode of use herein shown and described, since various modifications within the scope of the appended claims may occur to persons skilled in the art to which the invention pertains.

We claim:

1. An aquatic hunters' decoy comprising, a hollow unitary molded pulp body devoid of seams and of substantially uniform wall thickness, said body having an indentation forming a local recess in the base near the front portion thereof and being formed with a depending base projection providing an integral central longitudinal keel extending rearwardly from said local recess, said body also having a top opening surrounded by an exterior surface lying in a single plane and in substantial vertical alignment with said base recess for affording access to the body interior, and said body also being formed with a top recess in substantially the same vertical plane with said keel and extending rearwardly from a point on the edge of said single plane surface longitudinally of said body and substantially to the rear end thereof, attachment means extending through the body base within said base recess and provided with attachment portions respec-

tively located internally and externally of said body, a head having a neck portion penetrating the top opening of said body to normally seal the same, and means associated with the neck portion of said head and detachably connected to the internal attachment portion of said attachment means entirely within the interior of said body.

2. An aquatic hunters' decoy comprising, a hollow molded pulp body having a top opening surrounded by an exterior surface lying in a single plane, attachment means carried by the base of said body below said top opening and having an internal attachment portion, a head having a neck portion penetrating the top opening of said body to a normally seal the same and also having a surface lying in a single plane and adapted for seating on the single plane surface of said body, and resilient means associated with the neck portion of said head and detachably connected to the internal attachment portion of said attachment means entirely within the interior of said body whereby said head is maintained in seated position on said body to seal said top opening while being rotatable relative to said body, said body having a similar external surface contour over the front portion thereof extending substantially to opposite sides of the top opening and having a dissimilar surface contour rearwardly of said top opening, and said head having the lower external surface of its front portion of a contour substantially corresponding to the adjacent external surface of the front portion of the body whereby those portions will remain in substantially contacting slidable relation when the head is turned relative to said body while relative rotation thereof is limited by the body portion of dissimilar contour.

3. An aquatic hunters' decoy comprising, a hollow molded pulp body having a top opening, a head having a neck portion penetrating the top opening of said body to normally seal the same, and means for maintaining said head in seated position on said body to seal said top opening while permitting rotation of said head relative to said body, said body having a similar external surface contour over an extended front portion thereof and having a dissimilar surface contour rearwardly of said top opening, and said head having the lower external surface of its front portion of a contour substantially corresponding to the adjacent external surface of the front portion of the body whereby those portions will remain in substantially contacting slidable relation when the head is turned relative to said body while relative rotation thereof is limited by the body portion of dissimilar contour.
